(57) **CLAIM**

The ornamental design for bottomless bag insert, as shown
and described.

DESCRIPTION

FIG. 1 is a perspective view for a bottomless bag insert
showing my new design;

FIG. 2 is a top side view thereof;

FIG. 3 is a bottom view thereof;

FIG. 4 is a front view thereof, the back side view thereof
being a mirror image of that which is shown; and,

FIG. 5 is a left side view thereof, the right side view thereof
being a mirror image of that which is shown.
